BY Edwin H. Brown

his ATTORNEY.

UNITED STATES PATENT OFFICE.

JAMES S. SCOTT, OF NEW YORK, N. Y.

CAR-COUPING.

SPECIFICATION forming part of Letters Patent No. 511,278, dated December 19, 1893.

Application filed August 31, 1893. Serial No. 484,506. (No model.)

To all whom it may concern:

Be it known that I, JAMES S. SCOTT, of the city, county, and State of New York, have invented a certain new and useful Improvement 5 in Car-Couplers, of which the following is a specification.

I will describe a car coupler embodying my improvement, and then point out the novel features in the claims.

10 In the accompanying drawings Figure 1 is a plan or top view of a car coupler embodying my improvement. Fig. 2 is a side view of the same. Fig. 3 is a perspective view of a plate used in said coupler. Fig. 4 is a top 15 view of the knuckle of the coupler.

Similar letters of reference designate corresponding parts in all the figures.

A designates a coupler head and A' designates a shank extending from the same.

20 B' designates a knuckle having a main or outer portion b' and a locking portion b²; said knuckle being pivotally connected with one side or arm of the coupler head by means of a pivot pin C. The portion b' of the knuckle 25 may be bifurcated and provided with holes to enable it to be used with the ordinary link and pin.

D designates a vertically sliding pin fitted to a recess a formed vertically in the coupler 30 head rearward of the pivot pin C and intersecting a recess a' formed in the coupler head. As here shown this pin has a narrow lower portion, a wide upper portion and an inclined surface d intermediate of its narrow and wide 35 portions. Not only is this inclined surface inclined in a vertical direction, but it is preferably also inclined horizontally. The extremity of the inner portion b² of the knuckle is inclined reversely to the incline of the locking pin. Hence when the inner portion b² of 40 the knuckle is swung inwardly and comes in contact with the inclined surface of the locking pin, it will force the locking pin upwardly until it has passed the same. Then the locking pin will drop by gravity and as the surfaces of the locking pin and knuckle then in contact are flat, the knuckle will be enabled 45 to raise the locking pin and will be secured by the locking pin.

50 E designates a flexible or partly flexible

contrivance for operating the locking pin or device and for opening the knuckle. As here shown, it is made entirely flexible and consists of a chain which passes through an eye d' with which the upper portion of the locking pin is 55 provided, thence through an eye in a plate like portion or rib a' of the coupler head, and at the extremity is attached to an arm or appurtenance of the knuckle extending beyond the pivot pin of the same in the reverse direction to that in which the main or outer portion of the knuckle extends from said pivot pin. As here shown, the extremity of the chain connects with a plate G which has a 60 hole through which the pivot pin C passes, 65 it being secured in place by said pivot pin. This plate is engaged with the knuckle and in the present instance this engagement is effected by extending a pin g from the plate down into a hole formed in the upper part of 70 the outer or main portion b' of the knuckle. The extremity of the chain is connected to a pin g² extending upwardly from the plate G. The chain may be made fast to the locking pin, as distinguished from running through 75 the lever.

Obviously by pulling upwardly upon the flexible or partly flexible contrivance E, the locking device will first be disengaged from the knuckle and afterward the knuckle will 80 be oscillated to the open position.

It will be seen that by my improvement I provide a very simple and efficient means for engaging and opening the knuckle of a car 85 coupler.

I have filed another application for an improvement in car-couplings, the same having been designated Serial No. 485,921, setting forth a somewhat similar construction.

What I claim as my invention, and desire 90 to secure by Letters Patent, is—

1. The combination of a coupler head, a knuckle pivotally connected thereto, and a plate or lever pivotally connected with the coupler-head, and engaged with said knuckle 95 for the purpose of operating the knuckle, substantially as specified.

2. The combination with a coupler-head and knuckle pivotally connected thereto, a locking device for said knuckle, a plate or lever 100

pivots connected with the head and connected to the knuckle and an operating device flexibly connected with the said plate or lever and with the said locking device, substantially as specified.

3. The combination of a coupler head, a knuckle pivotally connected thereto, and a plate or lever secured in place by the pivot of the knuckle and engaged with said knuckle

for the purpose of operating the knuckle, substantially as specified.

In testimony whereof I have signed my name to this specification in the presence of two subscribing witnesses.

JAMES S. SCOTT.
